UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

BALL-BEARING FOR HARPS.

1,269,718.

Specification of Letters Patent. Patented June 18, 1918.

Application filed December 13, 1915. Serial No. 66,477.

To all whom it may concern:

Be it known, that I, WALTER I. KIRK, a citizen of the United States, residing at Chicago, in the county of Cook and State 5 of Illinois, have invented a certain new and useful Improvement in Ball-Bearings for Harps, of which the following is a full, clear, concise, and exact description, reference being had to the accompanying drawings, forming a part of this specification.

My invention relates to harps, and especially to the action thereof.

The principal objects of the invention are to provide a freer and more easily operating 15 harp action than heretofore; to avoid buzzing and vibration of the spindles in their mountings; and to secure other desirable results as will hereafter appear.

In the accompanying drawings Figure 1 is 20 an elevation of a harp having a portion of its neck broken away in order to show the action;

Fig. 2 is a vertical sectional view showing 25 a spindle or shaft and bearing therefor forming part of an action embodying my invention;

Figs. 3 and 4 are views on an enlarged scale of the opposite ends of said spindle or shaft.

Referring to Fig. 1 I show a harp A of 30 any suitable type or variety. Strings 1-1 are shown but these are not all the strings of the harp, the ones shown being an octave apart. At the harp neck I show the usual 35 side plates 2, and between the mechanism for engaging strings an octave apart so as to sharp all of such strings by movement of a pedal 4 at the base of the harp. Inasmuch as the general features of construction of this 40 pedal operated sharping mechanism are not involved in my present invention the same will not be further described. Each of such mechanisms, however, is provided with one or more spindles 5 extending between the side 45 plates 2 and 3, as shown in Fig. 2, and supported at its ends in such side plates. My present invention relates to these spindles and the bearings by which they are supported in the side plates 2 and 3. It will be apparent, however, that the construction hereinafter set forth could be employed for 50 other purposes.

Referring more particularly to Fig. 4 it will be seen that the spindle 5 is provided 55 at one end with a collar 6, having an in-

clined tapering or conical surface 7. This collar 6 is preferably made separate from the spindle 5 and fitted over a reduced end portion 8 of the latter. The part of the reduced portion 8 projecting beyond the collar 6 is preferably threaded as at 9. A disk 10 is fitted over the screw threaded end 9, being provided with a threaded socket by which it may be secured upon the end 9. This disk 10 is provided with pins or fingers 65 11 which are understood to be the string engaging pins or fingers adapted to engage the strings so as to sharp the same. As a bearing arrangement, the side plate 3 is provided with an aperture which is recessed 70 or enlarged sufficiently to receive an annular cup-shaped device 12 having its inner portion bent or extended inwardly as at 13 so as to form an annular ball race. Balls 14 are fitted within the member 12 and between 75 the same and the collar 6, so that the balls form a ball bearing for said collar. A small washer 15 is fitted into the outer or upper end of the member 12 so as to close the same and thereby hold the balls in position and 80 keep out dust and dirt. Thus it will be seen that a ball bearing construction is provided which is exceedingly simple and inexpensive, and at the same time is very effective and practical, permitting ready 85 assembling of the device. This assembling it will be seen, may be done by first fitting the ball bearing in place in the side plate or member 3, and then fitting the spindle in place and then screwing the disk 10 on to 90 the outer end of the reduced end 8 of said spindle. The entire ball bearing construction, it will be seen, is on the inner side of the plate 3 so that it is not visible upon the outer side thereof. A screw 20 passes 95 through the disk 10 into the end of the reduced portion 8, the threads of the portion 9 and of the pin 20 being of opposite character, one being right handed and the other left handed.

Fig. 3 shows the bearing for the other end of the spindle 5. This end of the spindle 5 is preferably provided with a small reduced end portion 16 which fits into a socket 17 which is screwed into the plate 2. A spring 18 is fitted in the socket member 17, and the reduced end 16 fits against said spring 18, said spring pressing against the end 16 so as to hold the spindle 5 snugly in the ball bearing at the other end of said spindle. 110

It will be understood that changes and modifications may be made without departing from the spirit of the invention.

What I claim is:

- 5 1. The combination with the side plates, of a spindle extending between the same, said spindle having one of its ends provided with a reduced portion which projects beyond the side plate at that end of the spindle, a cone shaped collar mounted upon the reduced end portion of said spindle, the ends of said collar being substantially flush with the sides of said plate, a member for engaging harp strings mounted on the reduced end portion of said spindle projecting beyond said collar and serving to clamp the collar in position, and an anti-friction bearing mounted in said plate and coöperating with said cone shaped collar.
- 10 15 2. The combination with the side plates of a spindle 5 extending between the same, said spindle having a reduced end portion

8 provided with a threaded portion 9, a collar 6 mounted upon the reduced end portion 8 and of substantially the width of the end plate 3, a disk 10 provided with a threaded socket adapted to fit over the threaded end portion 9, said disk 10 having a hub portion adapted to fit against the outer end of the collar 6, said collar 6 having its inner 30 end adapted to fit against the relatively large portion of the spindle 5, and an anti-friction bearing mounted in the inner side of said plate 3 and coöperating with the conical surface of the collar 6, said anti-friction bearing being concealed by the outer side of said plate 3.

In witness whereof, I hereunto subscribe my name this 24th day of November, A. D., 1915.

WALTER I. KIRK.
